DENTAL FLOSS HOLDER

Catherine Bolling Elcan, Hot Springs National Park, Ark.

Application April 3, 1937, Serial No. 134,892

5 Claims. (Cl. 132—92)

This invention relates to holders for dental floss and has for the primary object the provision of a device of this character for securing a strand of dental floss in a taut condition and in a position whereby it may be conveniently used for removing foreign matter from teeth.

Another object of this invention is the provision of a device of the above stated character which will fully protect the floss prior to use and will accommodate the floss after use and maintain the used floss separate from the clean floss so that the clean floss will not become contaminated.

A further object of this invention is the provision of a dental floss holder of the above stated character which will be simple, durable and efficient and which may be manufactured and sold at a low cost and may be conveniently carried within a person's pocket or pocketbook.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating a dental floss holder constructed in accordance with my invention.

Figure 2 is a sectional view taken on the line 2—2 of Figure 1.

Figure 3 is a transverse sectional view taken on the line 3—3 of Figure 2.

Figure 4 is a transverse sectional view taken on the line 4—4 of Figure 2.

Figure 5 is a transverse sectional view taken on the line 5—5 of Figure 2.

Referring in detail to the drawing, the numeral 1 indicates a main casing of substantially elliptical shape in cross section. One end of the casing is considerably reduced forming a sleeve 2 on which is rotatably mounted an operating cap 3. Another portion of the casing 1 is slightly reduced to form a sleeve 4 in which are arranged spaced partitions 5 and 6. At the point of formation of the sleeves of the casing 1 are internal and external shoulders 7 and 8. The internal shoulder 7 forms a seat for the partition 6 and the external shoulder 8 forms a seat for a closure cap 9 employed for closing one end of the casing 1. The partition 5 is secured in the sleeve 4 in any suitable manner so that it may be removed when desired. An operating shaft 10 is located in the casing 1 and one end is ro-

tatably supported by the partition 6 and the other end is secured to the cap 3. A spring dog 11 is secured to the shaft 10 and engages with the ratchet teeth 12 formed on the inner face of the sleeve 2 for the purpose of permitting the shaft 10 to be rotated in one direction by the cap 3 and be held against a reverse rotation.

The outer face of the casing has a knurled surface so that a firm grip can be obtained thereon. A spool shaft 10' is rotatably supported by the partitions 5 and 6 and is provided at one end with a head 12'. A spool 14 containing dental floss is secured on the shaft 10'. The shaft 10' is provided with angularly related faces 13 adjacent the head 12'. The space in the casing 1 between the partition 6 and cap 3 forms a chamber 17 to receive dental floss after being used and which winds on a spool 11' secured to the shaft 10.

Spaced ribs 18 are formed on the partition 20 and slidably support a locking plate 19. The locking plate has formed therein a substantially circular-shaped opening 20 and a slot 21 in communication therewith. The shaft 10' extends through the opening 20 and when located therein is free to rotate. However, on shifting the position of the plate 19 the slot 21 receives the angularly related faces of the shaft and thereby secures the shaft against rotation.

A rib 22 is formed on the plate 19 to provide 30 a finger piece to aid a person in sliding the plate 19 into its different positions.

Tubes 23 and 24 are secured to the sleeve 4 and extend outwardly therefrom and the tube 23 extends a short distance farther outwardly of the 35 sleeve than the tube 24. The cap 9 when applied to the sleeve covers said tubes. The tube 24 terminates within the chamber 17 while the tube 23 terminates within the space between the partitions 5 and 6. The dental floss from the spool 40 passes through the tube 23 thence through the tube 24 for winding onto the spool 11' within the chamber 17. The portion of the dental floss between the tubes 23 and 24 is disposed at an inclination and so positioned for the purpose of 45 permitting that portion of the floss to be easily engaged with and between teeth for the purpose of removing foreign matter.

A sleeve 26 is slidable in the tube 24 and through which the dental floss passes on leaving the tube 24 for winding on the shaft 10 within the chamber 17. The sleeve has a finger piece 27 which extends through a slot 28 in the casing 1 and by adjusting the sleeve endwise of the tube 24 the floss may be caused to change 55

its winding onto the spool 11' so that as the spool 11' becomes filled with used floss within the chamber 17 the feeding of further floss onto the spool 11' may be made in another place thereon by adjusting the sleeve 26. The slot 28 has an offset 29 in which the finger piece 27 may be moved when desiring to lock the sleeve against sliding movement.

In operation, when the locking plate 21 has been positioned to free the shaft 10' the shaft 10 may be rotated to unwind the floss from the spool on the shaft 10' onto the spool 11' within the chamber 17. It is to be understood that the winding of the floss from one spool to the other 15 spool only takes place when the portion of the floss has been employed or used which extends between the tubes 23 and 24 so that fresh floss may be brought into a usable position and the used floss wound on the spool 11' within the 20 chamber 17 and kept separate from the unused floss, thereby increasing sanitation of the device. After the floss has been adjusted to present a new portion between the tubes 23 and 24 the locking plate 21 is shifted to secure the shaft 25 10' and then by a slight rotation of the shaft 10 the floss may be drawn taut.

The formation of the sleeve 2 on the casing 1 defines a groove 34 and the edge of the cap is flanged or bent to lie in said groove whereby said 30 cap is rotatably mounted on the sleeve and prevented from accidentally pulling off of the sleeve.

What is claimed is:

1. A dental floss holder comprising a casing having chambers, a spool shaft journaled in one 35 of the chambers and having a spool of dental floss secured thereon, spaced tubes having the floss passing from the spool therethrough to present a portion of the floss in place for use, and means carried by said casing on which the floss 40 may be wound.

2. A dental floss holder comprising a casing having chambers, a spool shaft journaled in one of the chambers and having a spool of dental floss secured thereon, spaced tubes having the 45 floss passing from the spool therethrough to present a portion of the floss in place for use, an operating shaft journaled in the casing, a finger piece rotatably mounted on said casing, a ratchet drive between the finger piece and the operating shaft for rotating said operating shaft in one 50 direction to wind the floss thereon.

3. A dental floss holder comprising a casing

having chambers, a spool shaft journaled on one of the chambers and having a spool of dental floss secured thereon, spaced tubes having the floss passing from the spool therethrough to present a portion of the floss in place for use, an 5 operating shaft journaled in the casing, a finger piece rotatably mounted on said casing, a ratchet drive between the finger piece and the operating shaft for rotating said operating shaft in one direction to wind the floss thereon, a locking 10 means for the spool shaft whereby the floss may be tensioned by imparting a slight rotation to the operating shaft.

4. A dental floss holder comprising a casing having chambers, a spool shaft journaled in one 15 of the chambers and having a spool of dental floss secured thereon, spaced tubes having the floss passing from the spool therethrough to present a portion of the floss in place for use, an operating shaft journaled in the casing, a finger 20 piece rotatably mounted on said casing, a ratchet drive between the finger piece and the operating shaft for rotating said operating shaft in one direction to wind the floss thereon, a locking 25 means for the spool shaft whereby the floss may be tensioned by imparting slight rotation to the operating shaft, a cover removable from said 25 casing and overlying the tubes to protect the dental floss exposed between said tubes.

5. A dental floss holder comprising a casing 30 having chambers, a spool shaft journaled in one of the chambers and having a spool of dental floss secured thereon, spaced tubes having the floss passing from the spool therethrough to present a portion of the floss in place for use, an 35 operating shaft journaled in the casing, a second spool secured to the operating shaft, a finger piece rotatably mounted on said casing, a ratchet drive between the finger piece and the operating shaft for rotating the latter to wind used floss on 40 the second spool, a locking means for the spool shaft whereby the floss may be tensioned by imparting slight rotation to the operating shaft, a cover removable from said casing and overlying 45 the tubes to protect the dental floss exposed between said tubes, a sleeve slideable in one of said tubes, and a finger piece formed on said sleeve and extending outwardly of the casing whereby said sleeve may be adjusted endwise of its respective tube for varying the feeding of the 50 dental floss onto the operating shaft.

CATHERINE B. ELCAN.
